CLAIM

I claim the ornamental design of a massage and toning device, as shown and described.

DESCRIPTION

FIG. 1 is a top perspective view of a massage and toning device showing my new design;

FIG. 2 is a top plan view thereof;

FIG. 3 is a bottom plan view thereof;

FIG. 4 is a left side elevational view thereof;

FIG. 5 is a right side elevational view thereof;

FIG. 6 is a front side elevational view thereof; and,

FIG. 7 is a back side elevational view thereof.

The broken lines depicting a seam, a circular ring on the button element and a power-off symbol on the button element form no part of the claimed design.
